EXERCISING DEVICE

Anton Kraus, Chicago, Ill.

Application July 12, 1935, Serial No. 31,116

2 Claims. (Cl. 272—77)

My invention relates to exercising devices, and has among its objects and advantages the provision of an improved punching bag.

An object of my invention is to provide a 5 punching bag characterized by a quick recovery after being struck and in which the bag is shaped to simulate the head and body of a boxer. The bag also embodies a novel jointed structure operating to minimize the force of 10 the recoil and in which the head part of the bag is jointedly connected with the body.

In the accompanying drawing:

Fig. 1 is a plan view of the device;

Fig. 2 is a sectional view along the line 2—2 of 15 Fig. 1; and

Fig. 3 is a sectional view along the line 3—3 of Fig. 2.

In the embodiment selected to illustrate my invention, the figure 10, including a head part 12 20 and a body part 14, is mounted upon a standard 16 mounted upon a spring structure 18 fixedly connected with a plate 20 anchored to the floor 22. The spring 18 yields when the bag is struck to permit oscillation of the bag, and operates to 25 impart a quick return movement to the bag.

The body 14 comprises a covering 24 filled 30 with padding 26 such as curled hair or other suitable fibrous material. The covering 24 extends around the head 12 and has its bottom end sewed at 28 to a bottom part 30 having an opening for the reception of the shaft 32. The latter is provided with a flange 34 against which the part 30 bears. I place a plate 36 against the outer face of the part 30 and securely fasten 35 the latter between the flanges 34 and 36 by screws 38.

To the upper end of the shaft 32 I connect 40 a joint 40 which in turn is connected with a shaft 42 extending vertically through the head 12. The joint 40 is of a bendable nature to permit bending of the punching bag at a point slightly below the neck 44. When the device is struck above the joint 40, the head portion is thrown back. In cases where the bag is struck 45 below or in the locality of the joint 40, the force imparts a bending action to the device. In addition to providing a jointed figure simulating the body of a boxer, the joint performs an important function in breaking the force of the 50 recoiling bag. When the back is struck during a rapid recovery movement, the bending action bends to break the force of the impact which might otherwise injure the user.

Specifically the joint 40 comprises a flanged 55 member 46 having threaded relation with the

threaded end 48 of the shaft 32. Similarly, the threaded end 50 of the shaft 42 is provided with a flanged member 52. Upon the neck parts 54 of the two members 46 and 52, I mount a coil spring 56. This spring is close wound, preferably with initial tension, and has threaded relation with the necks 54 of the members 46 and 52. Upon the spring I mount a rubber casing 58 to prevent the material of the bag from working between the convolutions of the spring. 10

Within the cover 24 encircling the head 12, I mount an inner covering 60. The lower end of this covering is wrapped firmly about the shaft 42 as at 62 adjacent the flange 64 upon the shaft. The upper end of the shaft 42 is provided with 15 a flange 66 against which the covering 60 lies. I position a disc 68 in vertical alignment with the flange 66 and pinch the coverings 24 and 60 securely therebetween by means of screws 70.

One end of the spring 72 of the structure 18 20 has threaded relation with a post 74 having a neck 76 at its lower end. This neck passes through an opening in the plate 20 and is firmly secured thereby by riveting the end of the neck. The upper end of the spring 72 has threaded 25 relation with a sleeve 78 slidably mounted upon the shaft 32.

I mount a cone shaped tube 86 upon a flange 84 through the medium of screws 88. This flange has its upper end terminating in close 30 relation with the bottom of the body 10. The tube 86 enhances the ornamental appearance of the bag.

Within the spring 72 I mount a second spring 90 of the same type as the spring 56. One end 35 of the spring 90 has threaded relation with a post 92 positioned within the bore 94 in the post 74. The post 92 passes through an opening 96 in the post 74 and is made secure by riveting its end at 98.

The lower end of the shaft 32 has a threaded reach 100 upon which I mount a flanged member 102 for connection with the spring 90. The member 102 has threaded relation with the spring 90. Normally the spring structure 18 45 supports the bag in the vertical position of Fig. 1. The spring structure imparts a rapid rebound of the figure so as to position the figure in a vertical position by the time that the user is ready for another blow.

In providing a padded figure, I eliminate the necessity for inflating equipment. The bag structure is of durable construction in that I eliminate deflation of the bag in the event of damage to the covering. In addition, the bag 50

is padded to a degree of firmness simulating the body of an adversary.

Without further elaboration, the foregoing will so fully explain my invention that others may, 5 by applying current knowledge, readily adapt the same for use under various conditions of service.

I claim:

1. An exercising device comprising a striking bag including a lower part and an upper part, 10 shafts extending through portions of said parts and being arranged in spaced, axial alignment, said shafts being anchored to said parts, said parts being padded with a resilient material, a 15 resilient universal connection between said shaft parts and housed within the striking bag, said resilient universal connection operating to urge the shaft parts to their axial aligned positions, a base, and resilient means connecting the base

with one of said shafts for urging the bag toward a vertical position and effecting a quick recovery of the bag.

2. An exercising device comprising a striking bag including a lower part and an upper part, 5 said bag being padded with a resilient material, shafts positioned within both parts and normally arranged in axial alignment, a convoluted spring having its ends connected with said shafts, said spring urging the shafts to their 10 normal position, a tube of resilient material enclosing the convoluted spring, to prevent padding from working between the convolutions of the spring, one of said shafts extending to a position exteriorly of the striking bag, a base, 15 and a resilient connection between the base and the shaft part extending exteriorly of the bag.

ANTON KRAUS.
